9 Sheets-Sheet 9

UNITED STATES PATENT OFFICE.

GEORGE J. NETH, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed December 8, 1927. Serial No. 238,637.

My invention relates to autographic registers.

It is the object of my invention to provide an autographic register in which the several 5 superimposed paper sheets will be aligned by the movement of the writing table, and particularly by the engagement of the writing table with the creases transversely of the sheets along which creases the paper can be 10 aligned. It will be understood that the paper is supplied in packs with the several sheets riding one on the other and folded along their creased lines, the creased lines being adjacent one to the other, although 15 there are other means of supply, such as paper perforated transversely and carried on rolls which can likewise be handled by this machine.

It is my object to provide a machine in 20 which by a single continuous movement of the crank handle it is possible to eject any length of sheet desired, according to the setting of the machine so that one standard machine will be adaptable to all the commercial 25 lengths of register tickets currently used.

It is a further object to provide a machine in which this single continuous movement of the handle will bring about a feeding of the slips and storing of one of the sheets, a separation of the feeding rolls with the cessation 30 of feeding, the restraint of the rolls from further rotation, the alignment of the sheets and the movement of the handle without moving the rolls so as to bring the handle to initial 35 starting position again, with incidental clamping of the sheets so that at the end of the handle movement the sheets to be ejected may be torn off.

It is my object to provide a sequence of 40 movements, in which the handle first ejects the sheets, then the rolls are spread apart, and are stopped from continuing to rotate, the writing table is moved backwardly to align the sheets along their creases drawing 45 the sheets backwardly slightly, and then the handle being brought to its initial starting position again the sheets are clamped or re-engaged by the ejecting rollers.

The preferred method of handling paper 50 sheets is to remove them from a pack in a storage compartment and deliver the storage or record sheet into a second storage compartment in pack form so that the record may be

easily stored and easily filed in the records of the person owning the register. 55

Referring to the drawings:

Figure 1 is a top plan view of the complete register, showing a typical form printed on one of the tickets to be ejected, such form showing through the writing opening of the 60 cover plate.

Figure 2 is a side elevation from the handle side of the register.

Figure 3 is a section on the line 3—3 of Figure 1, looking in the direction of the arrows. 65

Figure 4 is a section on the line 4—4 of Figure 2, looking in the direction of the arrows.

Figure 5 is an enlarged section on the line 70 5—5 of Figure 1.

Figure 6 is an enlarged view of the writing table at one end, the paper sheets and the guiding rolls, with the aligning abutment showing the writing table and sheets in 75 aligned position with the writing table at its rearmost position.

Figure 7 is a section on the line 7—7 of Figure 9, looking in the direction of the arrows, showing the parts of the ejection roll, 80 locking and unlocking mechanism in position.

Figure 8 is a similar view, showing the parts in position.

Figure 9 is an enlarged section on the line 85 9—9 of Figure 2.

Figure 10 is a perspective of the clutch arm.

Figure 11 is a perspective of the clutch roll support.

Figure 12 is a section on the line 12—12 90 of Figure 9, showing the roller clutch used for permitting the handle to continue to move to its home position, while all the gearing carried by the handle, shaft and the rolls is stationary. 95

Figure 13 is an enlarged view of the aligning dial and final ejecting distance dial with the handle showing in full line in dotted position to indicate the positions at which the handle will be when the several steps of operation take place in the machine, with the clutch pins in the positions indicated. 100

Figure 14 is an enlarged plan view of the cam setting dial.

Figure 15 is a diagrammatic chart illustrating the steps of movement, with lengths 105

of movement of the paper for a typical $4\frac{1}{2}$ " ticket.

5 Figure 17 is a section on the line 17—17 of Figure 9.

Figure 18 is a section on the line 3—B of Figure 1, showing the table rearmost positions.

10 Referring to the drawings in detail, 1 designates a bottom for the autographic register casing. This casing is provided with side walls 2 and 3. An end wall may be provided or not as desired, but in the present instance 15 it has been removed for the purpose of clarity. The supply storage box, consisting of a rear wall 4, side walls 5, front wall 6 and bottom wall 7 fills the rear portion of the register casing. This box is supported upon a bottom support 8 in the bottom of the register. The box itself contains a plurality of superimposed sheets, generally designated 9, which are creased along the creased lines 70, the creased lines being superimposed one over 20 the other.

These sheets are fed upwardly between guiding members or rollers 11 and 12, which are held in spaced relationship below the general level of the writing table 13, and in 30 spaced relationship from the transverse aligning abutment 14 held between the side walls 2 and 3 at the top of the register casing just beneath the writing cover 15.

35 The paper sheets pass between the roll 12 and the aligning abutment 14, upwardly and thence forwardly over the writing table 13. The cover plate 15 is provided with the usual writing opening 16 and roll cover 17, which terminates in the sharp edge 18 against which the ejected sheets are torn off.

40 The writing table 13 is supported upon transverse rollers 19. Any form of support may be employed so as to facilitate a free fore and aft movement of the writing table.

45 Depending from the forward bottom portion of the writing table are a pair of brackets 20 adapted to form spaced shoulders with which the arm 21, known as the writing table actuating arm, engages. This arm is provided with a head 22, which projects into an aperture 23 in the plate, which aperture is located between the shoulders 20.

50 The rear edge of the writing table is tapered from the bottom of the table upwardly 55 into a sharp edge as at 24 so as to facilitate the insertion of a sharp accurate aligning edge into the fold or crease 10 of the sheets 9 against the abutment 14 to secure accurate alignment.

55 60 The arm 21 is moved backwardly against the resistance of a spring 25, mounted on a stud 26 on the side wall 3. This movement is effected by the rotation of the main actuating handle shaft 27, which carries a writing table actuating cam 28.

In order to permit of the rearward movement of the writing table, which carries along with it the sheets to align them against the abutment 14, it is, of course, necessary to release the sheets from driving engagement 70 with the ejecting rollers 29 and 30. These rollers are superimposed and are synchronized in their driving movement together by having internmeshing gears 31 and 32. These gears are driven from the shaft 27 through a master actuating gear 33 and intermediate 75 pinions 34 and 35.

The pinions 34 and 35 are carried on a stud shaft 36 mounted on the side wall of the register. The shaft 27 carries an actuating handle 37, which is stopped at the end of the cycle of movement by the movable stop 38. The roller 29 is provided with a ratchet 39 with which a pawl 40 engages when the driving movement of the rollers ceases, as will be hereinafter explained. The purpose of this pawl is to prevent the rollers continuing to turn, due to their momentum, and thus continuing to eject the sheets when it is desired that the ejection shall cease and the aligning 85 operation commence and be executed. This pawl is forced into engagement with the teeth 80 of the ratchet 39 by a spring 41, and is moved out of engagement by the ratchet cam 41a.

90 The rolls are spread apart through the agency of a third cam mounted on the driving shaft 27, said cam being designated 42 and known as the roll spreading cam. This cam operates a lever 43 pivoted at 44 on the side wall 3 of the register. This lever at its lower 95 end engages with an arm 45 on the cam sleeve 46 mounted upon the transverse shaft 47. The rotation of this cam sleeve 46 serves to elevate a roll spreading yoke and arm 48, which engage with the upper roller to elevate it. 100 This arm is guided in its reciprocatory movement by studs 49 working in slots 50 in the arm 48.

105 The shaft 47 with the cam sleeve 46 may be independently manually operated through 110 the button on the outside of the register having a knurled surface and designated 51.

The cams mounted on the shaft 27 are carried on a sleeve 52, which is provided with 115 graduations 53 to indicate the length of the sheet to be ejected. This sleeve has on one end ratchet teeth 54 engaging with corresponding teeth 55 on a second sleeve 56 independently attached to the shaft 27. Thus the positioning of the cams to effect the proper ejection may be secured with respect to the shaft 27. The engagement of these sleeves one with the other through their teeth 54 and 55 is maintained by a coil spring pressing the sleeve 52 against the sleeve 56. Such 120 spring is designated 57. The other end of the spring abuts against the side wall 3.

125 The driving shaft 27 has two clutches mounted upon it. The clutch mechanism, which is shown in Figures 7, 8, 9, 10 and 11, 130

is used for disconnecting the driving shaft 27, and the master gear 33, with its associated gears 34, 35, 31 and 32 driving the rolls used for ejecting the sheets. The mechanism shown in Figures 9 and 12 is in the nature of a brake clutch to prevent the gears from continuing to spin after they have been de-clutched from the driving shaft 27.

This brake clutch consists of a sleeve 58 mounted on the shaft 27 by the set screw 59, or other means which has cutaway roller slots 60 in which are mounted spring-pressed rollers 61, pressed outwardly tangentially of the sleeve 58 by the spring 62 so as to engage with the inside of a drum 63 carried on a sleeve 64 attached by a set screw 65 to a third sleeve 66, which is integral with the gear 33 that is loosely mounted upon the shaft 27 so that when the gear 33 is halted in its movement the shaft will continue to rotate until the operator has brought the handle to its home position.

The roller clutch just described normally connects this gear 33 and its sleeve 66 to the shaft 27, but when it is disconnected the clutch effect is only sufficient to prevent the gear 33 from spinning, due to its momentum, while at the same time the clutch is not sufficiently strong and positive to carry the gear 33 with the shaft 27 but is allowed to slip relative thereto and stay in its position of rest. This roller clutch is known as an anti-spinning gear clutch.

The gear clutch proper consists of a drum 67 extending laterally of the gear 33. This drum has pivoted on the inside of it a clutch roll support, designated 68. This clutch roll support is U-shaped with arcuate arms having a pivot 69 connecting the arms and a roller 70 mounted in slots 71 in the ends of the arms adapted to move transversely of the arms. One of the arms is provided with a cam head 72.

The rear end 73 of this clutch roll support is provided with a shoulder 74. A helical spring 75 is mounted on the pivot support 69, between the arms of the clutch roll support. One end of this spring engages with the inside of the end member 73 and the other end of the spring engages with the end of the clutch arm 76, between whose jaws 77 the clutch roll support is pivoted, the roller 70 being adapted to engage with the outer cam surface 78 of the clutch arm 76. This clutch arm 76 is mounted upon the shaft 27 and turns with it.

The clutch arm also carries a pair of jaws 79, on which is pivoted a spring-pressed finger 80 controlled by the spring 81 mounted around its pivot 82. A pin 83 projects through the side wall 2. This pin 83 is carried on a ring 84, and projects through a slot 85 in an outside dial plate 86. The ring 84 is provided with an arm 87 that has a hooked end 88 engaging with the second pin 89,

which is removably mounted in the holes 90 in the dial plate 86. A second outside dial segment 91 is also provided for a purpose hereinafter described.

The pin 83 is adapted to project in the path 70 of the locking finger 80 and causes it to be held temporarily to permit the shoulder 74 of the clutch roll support to drop downwardly to bring the roller 70 into clutching position. Thus the shaft 27 and the gear 33 will be 75 clutched together by reason of the roller 70 being caught between the cam face 78 and the drum 67. It is held in that locking position by the spring 75.

It is unlocked from that position by the pin 80 89 engaging the clutch roll support cam face 72 and depressing the roll, thus causing disengagement. When this occurs the arm 80 gets under the shoulder 74 and holds the roll in declutched position, permitting the shaft 85 to continue to turn without turning the gear 33 and its drum 67.

Thus the sequence of operation of this clutch is as follows: The rotating shaft 27 carrying with it the arm 76 and the clutch 90 roll support pivoted on the end thereof also carries the gear 33 and its drum 67 with it by reason of the spring pressed engagement of the roller 70 with the inside of the drum 67. The gear 33 and the shaft 27 turn together through a major portion of the revolution of the shaft 27 while the paper is being ejected, but this gear movement is discontinued when the pin 89 engages the cam face 72, depressing it and thus releasing the engagement. When this occurs the spring-pressed support 80 comes beneath the shoulder 74 and holds the clutch roll support and its roll in disengaging position.

In order to restore the clutch roll to its 105 unlocking position, where it can again serve to clutch and join the shaft 27 to the gear 33, I use the pin 83, which is interposed in the path of the stop or support 80 at a point where that stop will be held temporarily to permit 110 the clutch roll to reengage approximately at the end of the handle stroke in order that the gear and shaft will be clutched together, when a new cycle of operations starts once more.

Method of operation of the whole register.

Assume the handle 37 to be in the position shown in Figure 2. The ejecting rollers are in engagement with the paper sheets. Internally the parts are in position shown in 120 Figure 3, with the writing table in its forward position.

When the several sheets are written upon and duplicate copies made by reason of the conventional carbon paper 92, which is fed 125 from the roll 93 in the box 94, the finger piece 38 is moved and the handle started through a cycle of operations. This cycle is completed by a complete revolution of the handle.

During the first portion of the movement of the handle the shaft 27 rotates, carrying the gear 33 with it, which results in the rotation of the rollers and the ejecting of the sheets which are to be ejected and the feeding of the record sheet 95 between the record guides 96 and 97 into the record box 98 beneath the forward cover 99.

When this ejection has been completed and it is then desired to align, the aligning cam 28 will have been brought to a position where it will move the arm 21 backwardly, thus moving the writing table to the rear until the end 24 of the writing table engages along the creases 10 of the sheets and aligns them along these creases against the abutment 14, whereupon the cam having passed by the spring on the arm 21 moves the writing table forwardly again.

Simultaneously with this aligning operation, just at the beginning thereof, in order to permit the sheets to be moved backwardly for alignment, the rolls are spread through the spreading cam 42. This cam 42 works upon the arm or lever 43, rotating the sleeve 46 and elevating the arm and yoke 48 spreading the rolls. Simultaneously with this cessation of the driving of the rolls, the ratchet 40 drops into the teeth 39 of the lower roll. This is permitted by the low point of the cam 41 coming into position, allowing the arm 40 to move under the impulse of the spring 41. If it is desired, the stopping of the rotation of the rollers may be effected just slightly before the spreading operation takes place.

To prevent the gears from continuing to rotate by their momentum, the clutch known as the anti-spinning gear clutch operates as heretofore described, and the rollers have ceased to operate through the gears by reason of the gear clutch having come into operation, according to the setting of the pin 89. This pin can be adjusted in the proper hole 90 in the dial plate 86, according to the length of sheet to be ejected. A similar adjustment is effected with reference to the cams through the graduations 53 on the sleeve 52. The unlocking point for reengagement of the gears with the shaft 27 is determined by the pin 83.

Thus, by making these adjustments the same machine is adapted for use with any of the conventional lengths of slips to be ejected. On the machine shown, although any lengths can be handled, I have shown a machine that is capable of handling checks from 3" in length to 11" in length, with half-inch differences in length between checks.

According to my method of operation of this machine I run out with the first rotation of the rollers a given length of ticket; then stop the rollers and spread them; then align the paper by pulling it back to the aligning position along the crease, which is a backward movement of $\frac{3}{8}$ ", and then reengage the paper with the rollers if any additional

paper need be run out in order to make a full length discharge for the check.

The following is a tabulation of the distances paper must be moved if it is printed up in checks ranging from 3" to 11". The first item is the length of the check, the second item is the length of the paper that must be run out prior to aligning, and the third item is the length of paper that must be run out after aligning. In the case of the 5½" check and the 11" check, as the first run out equals the length of the check, no additional run out is necessary so that there is no space indicated under the line-up column. The tabulation is as follows:

3" Check	Run out 1"	Line up draw 2"
3½" Check	Run out 3"	Line up draw ½" 85
4" Check	Run out 1"	Line up draw 3"
4½" Check	Run out 2½"	Line up draw 2"
5" Check	Run out 4"	Line up draw 1" 90
5½" Check	Run out 5½"	Line up
6" Check	Run out 1"	Line up draw 5" 95
6½" Check	Run out 2"	Line up draw 4½"
7" Check	Run out 3"	Line up draw 4"
7½" Check	Run out 4"	Line up draw 3½" 100
8" Check	Run out 5"	Line up draw 3"
8½" Check	Run out 6"	Line up draw 2½" 105
9" Check	Run out 7"	Line up draw 2"
9½" Check	Run out 8"	Line up draw 1½"
10" Check	Run out 9"	Line up draw 1" 110
10½" Check	Run out 10"	Line up draw ½"
11" Check	Run out 11"	Line up 115

In Figures 13 and 14 the location of the pin 89 should correspond in its numbered position to the member opposite the hair line 53^a. The graduations 53 on the cam sleeve 52 can thus be adjusted and the cams positioned.

The aligning dial 86 with the pin in the 2½" position should have the hair line 53^a opposite the 2½" position on the sleeve 52. The pin 83 should be so positioned that its arm 88 will be opposite the 2" position on the final ejecting dial 91. Thus the paper will be run out by the handle moving to the position shown in dotted lines at A, at which time the clutch connecting the gears to the shaft 27 will be disconnected and the aligning opera- 130

tion will take place until the handle reaches the dotted line position, marked B, at which time the clutch pin 83 will cause the clutch to again connect the gears to the driving shaft 5 27 and the rollers will be operated to eject the sheet an additional 2", which ejection is terminated by the handle coming to rest against its stop in the position C.

In the chart in Figure 15 this paper movement for a 4½" check is diagrammatically 10 illustrated. The first stage of the movement of the paper to aligning position is an ejection of 2½", the second stage is the aligning movement backwardly ¾" and third is the 15 final ejection movement of 2".

As the stopping of the rolls at the end of the final 2" movement must be extremely accurate and very positive, I have provided the protection clutch, shown in section in Figure 20 12, which prevents the momentum of the rollers from causing them to continue to spin and therefore to continue to eject when the handle is suddenly brought to rest against the stop at the end of the final ejecting movement. 25 This clutch is also useful in bringing about the same result in cooperation with the ratchet and pawl mechanism when the termination of the first ejection operation takes place, which in the case of the 5½" and 11" 30 checks is the only ejection movement of the rollers.

I thus provide a machine which is capable of being quickly adjusted to any length of 35 check. The normal commercial range of these checks, according to trade custom, is from 3" to 11". This greatly simplifies the manufacturing process, enabling a standard machine to be made, and is of great advantage to the customer in that a change in 40 his business system with respect to the length of his checks does not necessitate the purchase of a new machine.

It will be understood that by creases I mean any form of aligning designation for physical transformation of the paper to facilitate 45 the alignment, such as perforations, grooves, creases, folds and bends. It is not necessary to have the paper initially folded for this purpose, but it may be supplied in rolls, as for 50 instance, rolls that are transversely perforated at spaced intervals.

I desire to comprehend within my invention such modifications as may be clearly embraced within my claims and the scope of my 55 invention.

Having thus fully described my invention, what I claim is new and desire to secure by Letters Patent, is:

1. In an autographic register using a plurality of superimposed sheets, means for ejecting the sheets, a writing table over which the sheets pass, and means for moving the writing table against the sheets to align them.

2. In an autographic register using a plurality of superimposed sheets with transverse

creases at spaced intervals, means to eject the sheets, a writing table over which the sheets pass, and means for moving said writing table against said sheets to engage the said creases to align them along the creases.

70

3. In an autographic register using a plurality of superimposed sheets with transverse creases at spaced intervals, means to eject the sheets, a writing table over which the sheets pass, means for moving said writing table 75 against said sheets to engage the said creases to align them along the creases, and a stationary abutment against which said sheets are aligned along their creases.

4. In an autographic register using a plurality of paper sheets superimposed one over the other in folded condition, means arranged for delivery of said sheets with the creases of their folds superimposed and to eject said sheets, means consisting of a writing table to 80 support the sheets, means to move the writing table against the creases of said sheets to align them on the creases.

5. In an autographic register using a plurality of paper sheets superimposed one over 90 the other in a folded condition, means arranged for delivery of said sheets with the creases of their folds superimposed and to eject said sheets, means consisting of a writing table to support the sheets, means to move the writing table against the creases of said sheets to align them on the creases, and means to render the ejecting means inoperative while the sheets are moved for alignment by the moving writing table.

6. In an autographic register using a plurality of paper sheets superimposed one over the other in folded condition, means arranged for delivery of said sheets with the creases of their folds superimposed and to 105 eject said sheets, means consisting of a writing table to support the sheets, means to move the writing table against the creases of said sheets to align them on the creases, means to render the ejecting means inoperative while 110 the sheets are moved for alignment by the moving writing table, and an abutment adapted to limit the movement of the writing table and the sheets being so aligned whereby the sheets are engaged between the writing table 115 and the abutment in an aligned position along their superimposed creases.

7. In an autographic register using a plurality of superimposed sheets, means to eject said sheets, means to render said ejecting means 120 inoperative, a reciprocating writing table having one edge thereof adapted to engage said sheets, means for arranging said sheets below said writing table to pass upward and over one edge of said writing table 125 and thence to the ejecting means, and means to align said sheets by reciprocating said writing table so that the edge thereof will engage said sheets where the sheets pass over the edge thereof.

130

8. In an autographic register using a plurality of superimposed sheets, means to eject said sheets, means to render said ejecting means inoperative, a reciprocating writing table having one edge thereof adapted to engage said sheets, means for arranging said sheets below said writing table to pass upward and over one edge of said writing table and thence to the ejecting means, means to align said sheets by reciprocating said writing table so that the edge thereof will engage said sheets where the sheets pass over the edge thereof, and a stationary abutment so that the sheets will be engaged between the abutment and the end of the writing table over which they pass for aligning purposes. 70
9. In an autographic register using a plurality of superimposed sheets with spaced transverse creases, means to support said sheets in a superimposed pack form folded along said creases, means to guide said sheets over one edge and the top of a writing table, a writing table adapted to reciprocate, means to reciprocate the writing table, means to eject said sheets, means to stop operation of means to eject the sheets, and means when said ejecting means ceases to operate, to move said writing table, to align said sheets along the edge of the table where the edge of the table engages with the superimposed creases of the sheets. 85
10. In an autographic register using a plurality of superimposed sheets with spaced transverse creases, means to support said sheets in a superimposed pack form folded along said creases, means to guide said sheets over one edge and the top of a writing table, a writing table adapted to reciprocate, means to reciprocate the writing table, means to eject said sheets, means, when said ejecting means ceases to operate, to move said writing table may move to align said sheets along the edge of the table where the edge of the table engages with the superimposed creases of the sheets, and a stationary abutment for limiting the movement of said table and said sheets. 100
11. In an autographic register using a plurality of superimposed spaced transversely creased sheets, means to eject the sheets from the register, a writing table, means on an edge of the writing table to cause said sheets to be aligned along said creases and means to reciprocate the writing table. 115
12. In an autographic register using a plurality of superimposed spaced transversely creased sheets, means to eject the sheets from the register, a writing table, means on an edge of the writing table to cause said sheets to be aligned along said creases, and means to reciprocate the writing table, and an abutment for cooperating with said sheets and writing table in said alignment operation. 125
13. In an autographic register using a plurality of superimposed sheets with spaced adjacent superimposed creases, said sheets being arranged in a pack in folded condition in said register, a writing table above said pack, means below and to one side of the edge of said table for guiding said sheets over the edge thereof, means to eject said sheets, means to move said table to align said sheets along said creases. 130
14. In an autographic register using a plurality of superimposed sheets with spaced adjacent superimposed creases, said sheets being arranged in a pack in folded condition in said register, a writing table above said pack, means below and to one side of the edge of said table for guiding said sheets over the edge thereof, means to eject said sheets, means to move said table to align said sheets along said creases, and an abutment for cooperating in said aligning operation, said aligning means being so arranged as to cause the said sheets to be arranged along the aligning edge of the table both below and over the top of the table. 145
15. In an autographic register using a plurality of superimposed sheets provided with spaced transverse creases, ejecting rollers, a writing table, means to reciprocate the writing table, means to spread said rollers prior to and during the reciprocating of the writing table. 150
16. In an autographic register using a plurality of superimposed sheets provided with spaced transverse creases, ejecting rollers, a writing table, means to reciprocate the writing table, means to spread said rollers prior to and during the reciprocating of the writing table, and means to prevent the further rotation of said ejecting rollers at the end of the ejecting operation coincident with the spreading of the rollers. 165
17. In an autographic register using a plurality of superimposed sheets with spaced transverse creases in superimposed adjacent relationship, a reciprocable writing table adapted to have one edge engage with said creases to align them, an abutment for cooperating in said aligning operation, a driving means, ejecting rollers driven thereby, means to reciprocate the writing table driven by said driven means, means to render said ejecting means inoperative, and means to disconnect said ejecting means to cease the movement thereof. 180
18. In an autographic register using a plurality of sheets having spaced aligned creases, a reciprocable writing table for aligning the sheets, an abutment, a handle and driving shaft, means associated with said driving shaft for reciprocating said writing table, ejecting rollers, means for driving said rollers mounted on said shaft, means for spreading said rollers controlled by said shaft, said several means being so arranged that by the continued movement of the driving shaft the sheets will be ejected, the rollers will be 185

brought to rest and spread apart, the writing table will be moved for aligning the sheets and upon alignment the sheets will be reengaged by the rollers to be held in position for writing and tearing off of the sheets.

19. In an autographic register using a plurality of sheets having spaced aligned creases, a reciprocable writing table for aligning the sheets, an abutment, a handle and driving shaft, means associated with said driving shaft for reciprocating said writing table, ejecting rollers, means for driving said rollers mounted on said shaft, means for spreading said rollers controlled by said shaft, said several means being so arranged that by the continued movement of the driving shaft the sheets will be ejected, the rollers will be brought to rest and spread apart, the writing table will be moved for aligning the sheets and upon alignment the sheets will be reengaged by the rollers to be held in position for writing and tearing off of the sheets, and means for preventing the spinning of said rollers carried by said driving shaft.

20. In an autographic register using a plurality of sheets having spaced aligned creases, a reciprocable writing table for aligning the sheets, an abutment, a handle and driving shaft, means associated with said driving shaft for reciprocating said writing table, ejecting rollers, means for driving said rollers mounted on said shaft, means for spreading said rollers controlled by said shaft, said several means being so arranged that by the continued movement of the driving shaft the sheets will be ejected, the rollers will be brought to rest and spread apart, the writing table will be moved for aligning the sheets and upon alignment the sheets will be reengaged by the rollers to be held in position for writing and tearing off of the sheets, means for preventing the spinning of said rollers carried by said driving shaft, and means for preventing the spinning of the driving means of said rollers.

21. In an autographic register using a plurality of sheets having spaced aligned creases, a reciprocable writing table for aligning the sheets, an abutment, a handle and driving shaft, means associated with said driving shaft for reciprocating said writing table, ejecting rollers, means for driving said rollers mounted on said shaft, means for spreading said rollers controlled by said shaft, said several means being so arranged that by the continued movement of the driving shaft the sheets will be ejected, the rollers will be brought to rest and spread apart, the writing table will be moved for aligning the sheets and upon alignment the sheets will be reengaged by the rollers to be held in position for writing and tearing off of the sheets, means for preventing the spinning of said rollers carried by said driving shaft, means for preventing the spinning of the driving means of

said rollers, and yielding means for restoring said writing table to its initial position after the aligning operation.

22. In an autographic register using a plurality of sheets having spaced aligned creases, a reciprocating writing table for aligning the sheets, an abutment, a handle and driving shaft, means associated with said driving shaft for reciprocating said writing table, ejecting rollers, means for driving said rollers mounted on said shaft, means for spreading said rollers controlled by said shaft, said several means being so arranged that by the continued movement of the driving shaft the sheets will be ejected, the rollers will be brought to rest and spread apart, the writing table will be moved for aligning the sheets and upon alignment the sheets will be reengaged by the rollers to be held in position for writing and tearing off of the sheets, means for preventing the spinning of said rollers carried by said driving shaft, means for preventing the spinning of the driving means of said rollers, yielding means for restoring said writing table to its initial position after the aligning operation, and roller guiding means for guiding said sheets arranged beneath the rear end of said writing table so that the aligning edge of said table will be inserted in a V-shaped pocket formed by said sheets to facilitate alignment along the creases thereof.

23. In an autographic register using a plurality of superimposed sheets adapted to be aligned along spaced transverse creases, an actuating means, a writing table, means for ejecting said sheets, means for aligning said sheets along the creases including a backward movement of said sheets to an aligning position, means for spreading said ejecting means coincident with the aligning operation, and means to cause said sheets to be reengaged for further ejection to final ejecting position.

24. In an autographic register using a plurality of superimposed sheets adapted to be aligned along spaced transverse creases, an actuating means, a writing table, means for ejecting said sheets, means for aligning said sheets along the creases including a backward movement of said sheets to an aligning position, means for spreading said ejecting means coincident with the aligning operation, and means to cause said sheets to be reengaged for further ejection to final ejecting position, said actuating means for the aligning means and ejecting means being adapted to move in a continuous movement throughout the cycle of operation.

25. In an autographic register using a plurality of sheets having spaced aligned creases, actuating means, ejecting means, means to connect the actuating means and ejecting means, means to disconnect the actuating means from the ejecting means, means to disengage the ejecting means from operative re-

lationship with said sheets, means to align said sheets during said disengagement with the sheets, and means to adjust the ejection means to change its period of operation.

5 26. In an autographic register using a plurality of sheets having spaced aligned creases, actuating means, ejecting means, means to connect the actuating means and ejecting means, means to disconnect the actuating means from the ejecting means, means to disengage the ejecting means from operative relationship with said sheets, means to align said sheets during said disengagement with the sheets, and means to adjust the ejecting means to change its period of operation.

27. In an autographic register using a plurality of sheets having spaced aligned creases, actuating means, ejecting means, means to connect the actuating means and ejecting means, means to disconnect the actuating means from the ejecting means, means to disengage the ejecting means from operative relationship with said sheets, means to align said sheets during said disengagement with the sheets, and means to adjust the ejecting means to change its period of operation, said aligning means consisting of a reciprocating writing table and a stationary abutment whereby the backward movement of the table by the aligning means will serve to align the sheets along their creases between the rear edge of the table and the abutment.

28. In an autographic register using a plurality of sheets having spaced aligned creases, 35 an actuating means, ejecting rolls actuated thereby, means to connect said actuating means and rolls, means to bring said connecting means into operation, means to render said connecting means inoperative, setting dials for said respective means to bring the connecting means into operation and to render it inoperative whereby said ejecting means will operate during a portion of the time of the operation of the actuating means and will be rendered inoperative during another portion. 45

29. In an autographic register using a plurality of sheets having spaced aligned creases, an actuating means, ejecting rolls actuated thereby, means to connect said actuating means and rolls, means to bring said connecting means into operation, means to render said connecting means inoperative, setting dials for said respective means to bring the connecting means into operation and to render it inoperative whereby said ejecting means will operate during a portion of the time of the operation of the actuating means and will be rendered inoperative during another portion, and a means for effecting the alignment of said sheets and means to effect the disengagement of the ejecting means so that said alignment may take place during the period that the ejecting means is not operating.

65 30. In an autographic register using a plu-

rality of sheets having spaced aligned creases, an actuating means, ejecting rolls actuated thereby, means to connect said actuating means and rolls, means to bring said connecting means into operation, means to render said connecting means inoperative, setting dials for said respective means to bring the connecting means into operation and to render it inoperative whereby said ejecting means will operate during a portion of the time of the operation of the actuating means and will be rendered inoperative during another portion, and a means for effecting the alignment of said sheets, means to effect the disengagement of the ejecting means so that said alignment may take place during the period that the ejecting means is not operating, and a dial adapted to facilitate the setting of the aligning operation and the time of it with respect to the time of operation of the ejecting means.

31. In an autographic register using a plurality of sheets having spaced aligned creases, an actuating means, ejecting rolls actuated thereby, means to connect said actuating means and rolls, means to bring said connecting means into operation, means to render said connecting means inoperative, setting dials for said respective means to bring the connecting means into operation and to render it inoperative whereby said ejecting means will operate during a portion of the time of the operation of the actuating means and will be rendered inoperative during another portion, and a means for effecting the alignment of said sheets, means to effect the disengagement of the ejecting means so that said alignment may take place during the period that the ejecting means is not operating, a dial adapted to facilitate the setting of the aligning operation and the time of it with respect to the time of operation of the ejecting means, and means to prevent the rotation of the ejecting means. 90 95 100 105

32. In an autographic register using a plurality of sheets having spaced aligned creases, an actuating means, ejecting rolls actuated thereby, means to connect said actuating means and rolls, means to bring said connecting means into operation, means to render said connecting means inoperative, setting dials for said respective means to bring the connecting means into operation and to render it inoperative whereby said ejecting means will operate during a portion of the time of the operation of the actuating means and will be rendered inoperative during another portion, means for effecting the alignment of said sheets, means to effect the disengagement of the ejecting means so that said alignment may take place during the period that the ejecting means is not operating, a dial adapted to facilitate the setting of the alignment operation and the time of it with respect to the time of operation of the ejecting 130

means, means to prevent the rotation of the ejecting means at the end of the first movement of the ejecting means, and additional means for stopping the movement of the 5 ejecting means at the end of its second movement.

33. In an autographic register using a plurality of sheets having spaced aligned creases, an actuating shaft, means for actuating the 10 shaft adapted to pass through a complete revolution, means to stop the shaft at the end of the revolution, ejecting rollers driven thereby, means to spread said rollers, a cam on said shaft for effecting said spreading 15 through said spreading means, a ratchet on one of said rollers, a pawl adapted to engage said ratchet while said rollers are spread, a cam for controlling said pawl, yielding means to impel said pawl into engagement 20 with the ratchet, a reciprocating writing table, an arm adapted to reciprocate said table, a stationary abutment spaced from the end of said table, a cam on said shaft for actuating said table reciprocating arm, yielding 25 means for returning said reciprocating arm and table to initial position, a clutch connecting said shaft and said ejecting rollers, a clutch locking pin adapted to cause said clutch to engage and connect the shaft and 30 rollers, and a clutch unlocking pin adapted to unlock said clutch.

34. In an autographic register using a plurality of sheets having spaced aligned creases, an actuating shaft, means for actuating the 35 shaft adapted to pass through a complete revolution, means to stop the shaft at the end of the revolution, ejecting rollers driven thereby, means to spread said rollers, a cam on said shaft for effecting said spreading through 40 said spreading means, a ratchet on one of said rollers, a pawl adapted to engage said ratchet while said rollers are spread, a cam for controlling said pawl, yielding means to impel said pawl into engagement with the ratchet, a reciprocating writing table, an arm adapted 45 to reciprocate said table, a stationary abutment spaced from the end of said table, a cam on said shaft for actuating said table reciprocating arm, yielding means for returning 50 said reciprocating arm and table to initial position, a clutch connecting said shaft and said ejecting rollers, a clutch locking pin adapted to cause said clutch to engage and connect the shaft and rollers, a clutch unlocking pin adapted to unlock said clutch, and a revolvable sleeve on said shaft carrying said cams, and means for holding said sleeve in predetermined positions whereby the position of said cams with respect to said shaft

may be controlled and regulated for timing 60 the several operations of ejecting and aligning.

35. In an autographic register using a plurality of sheets having spaced aligned creases, an actuating shaft, means for actuating the 65 shaft adapted to pass through a complete revolution, means to stop the shaft at the end of the revolution, ejecting rollers driven thereby, means to spread said rollers, a cam on said shaft for effecting said spreading 70 through said spreading means, a ratchet on one of said rollers, a pawl adapted to engage said ratchet while said rollers are spread, a cam for controlling said pawl, yielding means to impel said pawl into engagement 75 with the ratchet, a reciprocating writing table, an arm adapted to reciprocate said table, a stationary abutment spaced from the end of said table, a cam on said shaft for actuating said table reciprocating arm, yielding 80 means for returning said reciprocating arm and table to initial position, a clutch connecting said shaft and said ejecting rollers, a clutch locking pin adapted to cause 85 said clutch to engage and connect the shaft and rollers, a clutch unlocking pin adapted to unlock said clutch, a revolvable sleeve on said shaft carrying said cams, means for holding said sleeve in predetermined positions whereby the position of said cams with respect to said shaft may be controlled and regulated 90 for timing the several operations of ejecting and aligning, and a clutch between said shaft and the means to connect said shaft to the rollers so that when the shaft is brought 95 to rest the rollers will be prevented from continuing to turn and eject.

36. In an autographic register using a plurality of sheets having spaced aligned creases, a supply storage box, a record storage box 100 adapted to receive alternately folded sheets along the creased lines, a writing table, means to guide one of said sheets from the writing table into the storage box, means to guide said sheets from the supply box beneath and over the rear edge of the said writing table, a stationary abutment adjacent the rear edge of the writing table, means to reciprocate the writing table for aligning the sheets, ejecting 105 rollers for ejecting the sheets and filling the storage box with a record sheet, common actuating means for the reciprocating table and the ejecting rollers, and means actuated thereby for rendering said rollers inoperative to eject while the reciprocating writing table 110 is aligning.

In testimony whereof, I affix my signature.
GEORGE J. NETH
